(57) **CLAIM**

(21) Appl. No.: **29/476,822**

The ornamental design for a beverageware lid with elastomeric ring, as shown and described.

(22) Filed: **Dec. 17, 2013**

DESCRIPTION

(51) **LOC (10) Cl.** **07-01**

FIG. 1 is a rear perspective view of the beverageware lid with

(52) **U.S. Cl.**

elastomeric ring showing my new design;

USPC **D7/392.1**

FIG. 2 is a rear perspective view thereof;

(58) **Field of Classification Search**

FIG. 3 is a rear perspective view thereof, the elastomeric strap

USPC D7/300, 300.1, 387, 392.1, 396.1,
D7/396.2, 396.5, 511, 629; D9/419, 434,
D9/435, 436, 438, 443, 444, 530, 569, 570,
D9/715, 719, 740; D11/1-5; D20/22;
40/665; 63/3, 5.1, 15.45; 206/409, 427,
206/428; 215/261, 352; 220/737, 739;
221/63

FIG. 4 is a front view thereof;

See application file for complete search history.

FIG. 5 is a rear view thereof;

FIG. 6 is a right side view thereof, the left side being a mirror
image;

FIG. 7 is a right-side partial cut-away view thereof;

FIG. 8 is a top view thereof; and,

FIG. 9 is a bottom view thereof.

The dash-dash-long dash lines represent boundaries of the
claimed design. The dash-dash broken lines and unshaded
surfaces bounded by broken lines form no part of the claimed
design. The dash-long dash line represents a cut-away portion
that forms no part of the claimed design.
